CLAIM

I claim the ornamental design for a mat, as shown and described.

DESCRIPTION

FIG. 1 is an upper perspective view of the mat showing my new design;

FIG. 2 is a lower perspective view of the design shown in FIG. 1;

FIG. 3 is a right side plan view of the design shown in FIG. 1;

FIG. 4 is a left side plan view of the design shown in FIG. 1;

FIG. 5 is a front plan view of the design shown in FIG. 1;

FIG. 6 is a back plan view of the design shown in FIG. 1;

FIG. 7 is a top plan view of the design shown in FIG. 1; and,

FIG. 8 is a bottom plan view of the design shown in FIG. 1.

The shade lines shown represent surface shading and not surface ornamentation, color, or material type.

1 Claim, 8 Drawing Sheets
